UNITED STATES PATENT OFFICE.

ARTHUR O. BRUNETTE, OF KELOWNA, BRITISH COLUMBIA, CANADA.

HEATER FOR SAWDUST OR COAL DUST.

Application filed May 11, 1925. Serial No. 29,533.

The present invention pertains to a novel heater designed particularly to burn saw dust or coal dust.

The principal object of the invention is the provision of a device of this character of such construction and adapted to perform effectively the above named function. The principal feature of the invention resides in a grate having a raised and pointed central portion, in conjunction with a fuel magazine adapted to discharge upon the raised portion at a regulable rate. The raised portion of the grate has for its purpose to spread the fuel in an even thickness. The rate of discharge from the magazine is controlled by a slideable sleeve mounted on the lower end of the magazine. The invention also provides for an over-draft and an under-draft acting on opposite sides of the grate whereby the fuel is burnt with a clear combustion. Another feature of the invention is a construction within the stove which affords proper circulation of the gases and prevents accumulation of them. The invention is fully disclosed in the following description and in the accompanying drawings, in which:

Figure 1 is a vertical section of the device; Figure 2 is a front elevation thereof;

Figure 3 is a section on the line 3—3 of Figure 1;

Figure 4 is a section on the line 4—4 of Figure 1;

Figure 5 is a section on the line 5—5 of Figure 1;

Figure 6 is a section on the line 6—6 of Figure 1; and

Figure 7 is a fragmentary vertical section taken at right angles to Figure 1.

Reference to these views will now be made by use of like characters which are employed to designate corresponding parts throughout.

The heater or stove comprises a lower cylindrical section 1 and a slightly larger upper cylindrical section 2. The latter is provided with a removable top 3 through which the fuel may be charged.

The bottom of the lower portion 1 contains a cylindrical ash-pit 4 spaced annularly as at 5 from the wall of the section. Above the wall of the ash-pit, an inclined deflecting hood 6 is secured to the wall of the section 1. An air draft device 7 enters the space 5, while a similar member 8 passes through

this space and communicates with the interior of the ash-pit.

The upper part of the ash-pit supports a circular grate 9 having a central raised portion 10. Although this portion is shown as conical, it may be square or otherwise polygonal, the essential feature being that its sides are sloped and convergent upwardly towards a point. This raised portion is formed with a plurality of slots 11 diverging from the center thereof. The remainder of the grate is formed with concentric circular slots 12 which are necessarily interrupted at intervals 13 in order to maintain the unity of the structure.

The bottom of the ash-pit is provided with a sliding door 14 through which the contents may be removed.

From the upper edge of the section 2 is suspended a shell 15 having tapered walls 75 and terminating in a cylindrical lower end 16. Cross arms 18 are supported in the upper part of the shell 15, and from these is suspended a tapered tubular member 19, the lower end of which is secured as at 20 to the wall of the shell. The interior of the member 19, together with portion of the shell 15 communicating therewith, comprises the fuel magazine of the stove. At the intersection of the arms 18 is provided a rotatable internally threaded boss 21. This member receives the upper threaded end of a rod 22 which extends downwardly throughout the length of the shell 15. An arm 23 is secured to the lower end of the rod and carries a sleeve 24 which is slideable on the cylindrical end 16 of the magazine.

The lower portion of the shell 15 is formed with apertures 25 which establish communication between the fire box of the stove and the space 26 between the shell and the member 19. This construction provides for an adequate flow of gases through the device to ventilate the same and to prevent accumulation of gases. The upper end of the magazine is formed with similar apertures 27 through which the gases return to the body of the stove so that they may radiate their heat through the wall of the section 2. The gases are then free to leave the stove through the flue 28 communicating with the interior of the section 2. The section 1 is provided with a door 29 through which access may be had to the interior for cleaning, repairing or replacing parts.

In the operation of the device, saw dust or coal dust is charged into the magazine by removal of the top 3. The rate of feed of the fuel upon the grate is determined by regulation of the sleeve 24. For example, if a slow feed is desired, the boss 21 is turned to bring the sleeve relatively close to the grate. For larger feeds, the sleeve is raised accordingly. The tapered nature of the central part 10 of the grate causes the fuel to spread evenly over the surface of the grate. The fresh air entering the space 5 through the damper 7 rises towards the hood 6 and is deflected thereby upon the fuel, whereby a clear combustion is obtained. For stronger firing, a relatively larger quantity of air is admitted into the ash-pit through the damper 8, this air causing an underdraft through the slots 11 and 12. A part of the gases given off by the burning fuel passes upwardly through the space 19 and downwardly along the wall of the section 2, transferring its heat through the latter as already described, and finally exhausting through the flue 28.

While a specific embodiment of the invention has been illustrated and described, it is to be understood that various alterations in the details of construction may be made without departing from the spirit of the invention as indicated by the appended claims.

Having thus fully described the invention, what I claim as new and desire to protect by Letters Patent is:—

1. A heater of the character described, comprising a body, a grate contained within said body, said grate having a raised central portion converging upwardly towards a point, said raised and remaining portion of the grate being formed with slots, a fuel magazine having its discharge end disposed over said raised portion, an internally threaded boss supported in the upper part of said magazine, a rod having one end threaded into said boss, said rod extending downwardly through the magazine, a sleeve supported by said rod and slidably on the discharge end of said magazine, an ash-pit surrounding said grate and spaced from said body, a damper communicating with the space between the ash-pit and the body, a deflecting hood supported over said space

and above the grate, and a second damper leading to the interior of said ash-pit.

2. A heater, comprising a casing, a grate supported within said casing, a casing suspended from the top of the aforesaid casing and converging toward the lower end, a hopper rigidly supported within the latter casing and spaced from the upper walls thereof, said hopper having its upper end open and communicating directly with the upper end of said inner casing, said inner casing having openings leading from the upper end into the interior of the outer casing and openings therethrough connecting the interior of said outer casing with the interior of the inner casing at a point adjacent the bottom of said hopper.

3. A heater comprising a casing, a grate supported within said casing, a shell supported from the top of the aforesaid casing within the same and having a convergent lower end, a tapered tubular member extending upwardly from the convergent lower portion of the shell forming a hopper spaced from the upper part of said shell, openings arranged in the convergent part of the shell at the outward side of the hopper, openings at the top of the shell communicating with the interior of the main casing, and a flue leading from the main casing above the convergent lower end of the hopper.

4. A heater comprising a casing, a cylindrical wall arranged in the bottom of said casing and spaced from the inner wall thereof, a grate arranged within said cylindrical wall above the bottom of the casing, regulated means for directing a supply of air into the space beneath said grate enclosed by the cylindrical wall, regulated means for directing air into the space between the casing and the cylindrical wall, an upwardly inclined flange extending inwardly from the wall of the casing and projecting over the top of the cylindrical inner wall in spaced relation to the upper end thereof and forming an annular baffle directing air from the annular space between said wall and the casing laterally inward and upwardly over the fire.

In witness whereof I have hereunto set my hand.

ARTHUR O. BRUNETTE.
